US00D746810S

(12) United States Design Patent
Fujimoto et al.

(10) Patent No.: US D746,810 S
(45) Date of Patent: * Jan. 5, 2016

(54) PERSONAL COMPUTER

- (71) Applicant: FUJITSU LIMITED, Kawasaki-shi, Kanagawa (JP)
- (72) Inventors: Masahiro Fujimoto, Tokyo (JP); Ichiro Itano, Chigasaki (JP); Yuki Iida, Yokohama (JP)
- (73) Assignee: FUJITSU LIMITED, Kawasaki (JP)
- () Term: 14 Years
- (21) Appl. No.: 29/485,694
- (22) Filed: Mar. 21, 2014

(30) Foreign Application Priority Data

- Sep. 27, 2013 (JP) 2013-022526
